UNITED STATES PATENT OFFICE.

HARLON A. CLIFFORD, OF GREENFIELD, MASSACHUSETTS, ASSIGNOR TO EMMA D. CLIFFORD, OF GREENFIELD, MASSACHUSETTS.

NAIL PULLER.

Application filed June 7, 1920. Serial No. 387,006.

To all whom it may concern:

Be it known that I, HARLON A. CLIFFORD, a citizen of the United States, residing at Greenfield, in the county of Franklin and State of Massachusetts, have invented a new and useful Nail Puller, of which the following is a specification.

This invention relates to nail pullers, and has for an object the provision of means for readily drawing a nail from a structure by employing an ordinary claw hammer; or when the nail is a relatively large one by employing a bar or a similar device in connection with the device.

Another object of the invention is to provide a nail puller of generally improved construction, whereby the device will be simple, durable and inexpensive in construction, as well as convenient, practical, efficient and serviceable in its use.

With the above and other objects in view which will appear as the description proceeds, the invention resides in the combination and arrangement of parts and in the details of construction hereinafter described and claimed, it being understood that within the scope of what is claimed, changes in the precise embodiment of the invention shown can be made without departing from the spirit of the invention.

The invention has been illustrated in its preferred embodiments in the accompanying drawings, wherein:—

Figure 1 is a side elevation of the device, showing it in use;

Figure 2 is a similar view, but showing a claw-bar or the like device in use with the device;

Figure 3 is an edge view of the device per se.

Referring to the drawings, there are shown opposed body members 1 and 2 which are pivotally united by means of a rivet or other securing device 3. The body member 2 has a gripping jaw 4 extending from one terminal thereof, and a fulcrum member or foot 5 extends from the opposed terminal of the body member 2. The outer or operative face 6 of the foot member 5 is shaped to define a compound curve, the curves of the least radii being disposed adjacent the claw 4 and the curves of the greatest radii being positioned away from the claw 4.

The body member 1 has a claw 7 which is adapted to coact with the claw 4 to grip the

head of a conventional nail N, and this body member has opposed recesses 8 formed in its lateral faces at a point removed from the claw 7. An arm 9 extends from the body member 1, and the upper face of the arm 9 coincides with the lower walls 10 of the recesses 8.

In use, the device is so positioned that the opposed jaws 4 and 7 engage the head of the nail N, and then the upper end of the body member 1 is struck with a hammer which drives the points of the jaws 4 and 7 under the head of the nail thereby securely gripping it. Now the claw of the hammer is placed in the recess 8, and the convexed portion of the claw engages the upper face of the arm 9. In this position the hammer handle is gripped and moved in the direction indicated by the arrow, which action causes the jaws 4 and 7 to securely hold the head of the nail, and continued movement in this direction withdraws the nail N from the material M. During the initial movement the device will be fulcrumed on the foot 5 at a point adjacent the jaws 4 and 7, but as the nail is withdrawn from the material the fulcrum point is shifted to points remote from the jaws and allows the nail to be drawn entirely from the material M.

The arm 9 is made relatively long so that hammers of various shaped claws may be successfully employed in connection with the device, and the long arm 9 also increases the leverage of the device.

When very large nails are to be pulled the hammer is removed and a claw-bar C or a heavy rod is positioned in recesses 8 and a portion of the bar rests in the arm 9. The bar C is then moved in the direction indicated by the arrow and the nail may be readily withdrawn. This arrangement provides means for pulling relatively large nails which could not be safely drawn with the usual claw hammer.

Having thus described my invention what is claimed is:—

A nail puller including opposed body members which are pivotally united, one of the body members having opposed recesses formed therein, a relatively long arm extending from the body member and positioned so that one longitudinal face coincides with the inner end walls of the recesses, a gripping jaw extending from the body

member, the opposed body member having a gripping jaw and a fulcrum foot, the fulcrum foot having its face which engages the material from which the nail is to be pulled formed to present a compound curve of such configuration that the curves of least radii are positioned adjacent the jaws and the curves of greatest radii being positioned away from said jaws, the point 10 of initial contact between the fulcrum foot

and the said material being located beneath the said arm.

In testimony that I claim the foregoing as my own, I have hereto affixed my signature in the presence of two witnesses. 15

HARLON A. CLIFFORD.
